UNITED STATES PATENT OFFICE.

FRANK J. HINDERLITER, OF TULSA, OKLAHOMA.

SLIP-RING SOCKET.

Application filed October 19, 1927. Serial No. 227,194.

My invention relates to fishing apparatus for use in the drilling of wells, and more particularly to a device which may be termed a slip ring socket adapted to be lowered into a well casing to engage and remove a broken drill part therefrom.

At present it is the practice to employ a collar socket to remove broken drill members from the bottom of the well. This device, however, cannot be satisfactorily utilized to remove a drilling bit out of a tight hole in a deep well.

An object of my invention is the provision of an improved fishing tool for removing broken tool parts from a well.

Another object of my invention is to provide a socket which is not only adapted to fish broken bits from a shallow well but may be used equally well to remove a broken bit from a tight hole in a deep well.

In accordance with the general features of my invention I provide a socket comprising telescoping sleeves and slips carried by one of said sleeves adapted to be uncovered by the movement of the other sleeve, whereby said slips will engage the broken drill part, said latter sleeve being movable by the broken drill member engaging the same.

In accordance with other features of the invention I provide means for preventing the movement of the movable sleeve by foreign matter such as mud or slime, whereby it will only be actuated when it is engaged by the broken drill member, thus enabling the slips to at all times engage either the movable sleeve or broken drill member. This means preferably takes the form of a wooden pin adapted to be sheared by the upward movement of the movable sleeve when the same is actuated by the engagement of it by the broken drill member.

Other objects and advantages of my invention will more fully appear from the following detailed description taken in connection with the accompanying drawings, which illustrate several embodiments thereof and in which:

Figure 1 is an elevation of my socket partly in section;

Figure 2 is an enlarged fragmentary sectional view of the lower part of the socket clearly showing the relative positions of the slideable sleeves;

Figure 3 is a sectional view similar to Fig-

ure 2 illustrating the device as being disposed in a well casing and showing the inner sleeve as being engaged by the upper end of the broken drill member;

Figure 4 is a sectional view similar to Figure 3, the well casing being omitted, illustrating the inner sleeve as being moved up by the drill part and showing how this sleeve shears the wooden pin;

Figure 5 is a sectional view similar to Figure 4 illustrating the uppermost position of the inner or movable sleeve of the socket, the broken drill part being wedged to the outer sleeve by the slips uncovered by the upward movement of the inner sleeve;

Figure 6 is a plan view of one of the slips;

Figure 7 is a sectional view taken on the line VII—VII of Figure 6 showing the construction of the slip, and

Figure 8 is a fragmentary view partly in section of a modified form of socket showing the socket as applied to a tubular member to be fished from a well, the socket including an inner member adapted to telescope the tubular member.

In the drawings:

Like reference characters designate similar parts throughout the several views.

The reference character 10 designates generally the body of my novel socket shown in Figure 1. The upper end of this body is provided with a threaded portion 11 adapted to be coupled to a string of pipe for lowering the socket into a well casing such as the casing 12 shown in Figure 3. The lower portion 13 of the tubular member is enlarged and provided with a bore 14. The extreme lower end of this portion 13 is cut on a slant, as indicated at 15, in order to provide the body portion with an eccentric point or portion 16 adapted to facilitate the alignment of the broken drill member with the bore 14, as will be more fully explained hereinafter.

Positioned within the bore 14 is a movable sleeve 17. This sleeve includes a pair of diametrically opposed elongated slots 18 through which extends a transverse pin 19 having its ends mounted at 20 in the annular wall comprising the body portion 13. Positioned above the pin 19 and disposed parallel thereto is a wooden pin 21 which also has its ends mounted in the wall of body portion 13. This pin is adapted to be sheared by the telescoping sleeve 17, as will become more

apparent with the progress of the present description. Communicating with the upper end of the bore 14 is a slanting hole or aperture 22 formed in the body 10. This 5 aperture 22 comprises an outlet for any water which might be forced up into the bore 14.

The lower end of body portion 13 is provided with a plurality of parallel annular grooves 23, in each of which is disposed an 10 annular slip or wedge 24. Each of the annular seats 23 is defined by a slanting surface 25 and a shoulder 26. The slip 24 has a wedge-like cross-section and is adapted to be seated in the groove or seat 23 with its outer 15 slanting surface 27 (Figure 7) opposite the slanting surface 25 defining the seat. In Figure 7 it will be noted that the slip 24 has a vertical inner surface provided with a plurality of teeth 28 adapted to bite into the drill 20 member when the socket is raised from the well. The slip 24 is in reality similar to a piston ring, inasmuch as it is provided with cooperable slanting edges 28'. In other words, I have provided a split annular slip 25 adapted to be mounted in the seat 23.

The operation of this form of my invention is briefly as follows:

The socket is lowered into the well casing 12 (Figure 3) until the lower end of the movable or telescoping sleeve 17 strikes the upper end of the broken drill member or pin 30. It will be readily evident that the eccentric point 16 on the lower end of the body portion 13 facilitates the alignment of the pin 30 with 30 the bore 14. The wooden pin 21 serves, during the lowering of the socket, to prevent the sleeve 17 from being displaced upwardly by any slime or mud which might be forced into the bore 14 of the body portion 11. However, 35 upon the engagement of this sleeve by the drill pin 30, the sleeve will be forced upwardly resulting in the shearing of the pin 21, as shown in Figure 4, whereby the sleeve is free to continue on its upward travel. This 40 broken pin 21 gravitates through the tube 17 until it strikes the upper end of the broken drill pin 30, as shown in Figure 5. It is to be understood that this pin 21 must be replaced after each use of the socket. Obviously as the sleeve 17 travels upwardly, it 45 uncovers the slips 24 which are immediately covered by the outer surface of the drill pin 30. This arrangement prevents the slips from being displaced from their seats. The 50 pin 19 normally serves as a means for preventing the sleeve 17 from accidentally falling out of the bore of body portion 11, as is evident from Figure 3. Of course, the slips 24, due to them frictionally engaging the 55 sleeve 17, will to a certain extent prevent the sleeve from gravitating from the body portion 11.

As shown in Figure 5, the sleeve 17 continues its upward movement in the bore 14 60 until it strikes the portion of the body de-

fining the upper end of the bore. When the sleeve reaches this position, both of the slips 24 will be in engagement with the drill pin 30. Also should any water or slime be forced into the portion 11 during the upward movement of the sleeve 17, the same is free to escape from the body portion through the aperture 22, as previously described. 70

Now obviously upon the upward movement of the device, as shown in Figure 5, the wedges or slips 24 will be forced downwardly into tight engagement with the pin 30, whereby the drill pin or member 30 is firmly wedged to the body portion 11 so that it may be withdrawn with the socket from the well 80 casing 12. 75

In Figure 8 I have illustrated a modification of my invention, wherein the slips 24' are adapted to engage the inner surface of tubular tool member 30'. This form of my 85 invention includes a body 31 adapted to be suitably coupled to a string of pipe (not shown). The lower portion of this body 31 is provided with a plurality of seats 23' adapted to receive annular slips 24' of the same construction as the slips 24. Extending through the body 31 is a passageway 32 which discharges into a slanting passageway 33 in the upper end of the body 31. This 90 passageway 32 is adapted to permit the slime or mud to escape from under the socket member 31 and through the slanting opening 33. 95

Disposed concentric with the body 31 and slidably mounted thereon is a sleeve 34 which is adapted to normally retain the slips 24' 100 in their respective seats 23'. 105

The body member 31 is provided with a pair of diametrically opposed openings 35, in each of which is disposed a pin 36. These pins have their outer ends normally extending over the top edge of the slidable sleeve 34. The operation of this form of the invention is briefly as follows:

Upon the lower end of the sleeve 34 striking the upper end of the tool member 30' to be removed from the well casing, it is held from further downward movement with the body 31, and as a result the lower end of the body member enters the opening of the tool member 30. As the slips 24' pass out from under the sleeve 34, they immediately come into contact with the inner surface of the member 30'. When as many of the slips 24' have entered the tool member 30 as is possible or as is required, the body member 31 comprising the socket may be moved upwardly. Obviously the upward movement of the body 31 will result in the slips 24' being wedged between the tool member 30' and the lower portion of the body 31, whereby the tool member 30' can be drawn upwardly with the socket. 110 115 120 125

Now, of course, it is to be understood that although I have illustrated and described in detail the preferred forms of my invention, 130

the invention is not to be thus limited, but only in so far as defined by the scope and spirit of the appended claims.

I claim as my invention:

1. In combination, in a device for fishing tool parts from a well, a tubular body member, slip means carried by and disposed within said body member, and a slidable sleeve disposed within and concentric with said body member arranged to normally hold the slip means in place and being movable upon it contacting the tool member to be removed from the well to allow the slip means to grip the tool member as said slip means is uncovered.
2. In combination, in a device for fishing tool parts from a well, a body member, slip means carried by said body member, a slid- 20 able sleeve disposed concentric with said body member arranged to normally hold the slip means in place and being movable upon it contacting the tool member to be removed from the well to allow the slip means to grip the tool member as said slip means is uncovered, and means for preventing displacement of said sleeve by foreign matter such as mud, said latter means being shearable by said sleeve upon the sleeve coming into engagement with the tool member.
3. In combination, in a device for fishing tool parts from a well, a body member, slip means carried by said body member, a slid- 20 able sleeve disposed concentric with said body member arranged to normally hold the slip means in place and being movable upon it contacting the tool member to be removed from the well to allow the slip means to grip the tool member as said slip means is uncovered, and means for preventing displacement of said sleeve by foreign matter, such as mud, said latter means comprising a pin arranged so as to be sheared when the sleeve is moved upwardly due to its striking the tool member.
4. In combination, in a device for fishing tool parts from a well, a tubular body member, a slip carried by said body member ar- 45 ranged to engage the tool part to be removed from the well, and means within said mem- ber for normally covering said slip movable upwardly when it strikes a tool part, whereby the slip will be allowed to grip the tool part.
5. In combination, in a device for fishing tool parts from a well, a tubular body mem- 55 ber, a slip mounted within and carried by said body member arranged to engage the tool part to be removed from the well, and means within said member for normally cov- ering said slip movable upwardly when it strikes a tool part, whereby the slip will be allowed to grip the tool part, said latter means comprising a sleeve disposed in tele- scoping relation with said body member.
6. In combination, in a device for fishing
- tool parts from a well, a body having its lower end provided with a bore, a movable sleeve disposed within said bore, ring-like slip means mounted in said body normally cov- 70 ered by said movable sleeve, and means asso- ciated with the lower end of the body for fa- cilitating the alignment of the tool part with the bore, said sleeve upon it being engaged by the tool part being movable upwardly so as to uncover and allow the slip means to 75 engage the tool part.
7. In combination, in a device for fishing tool parts from a well, a body having its lower end provided with a bore, a movable sleeve telescop- 80 ing said bore, slip means mounted in said body normally covered by said movable sleeve, and means associated with the lower end of the body for facilitating the align- 85 ment of the tool part with the bore, said sleeve being movable upwardly upon it being en- gaged by the tool part so as to uncover and allow the slip means to engage the tool part, said slip means comprising a ring-like wedge having its internal surface provided with a 90 plurality of teeth for biting into the tool part upon the upward movement of the body, whereby the tool part will be removed with the body from the well.
8. In combination, in a device for fishing tool parts from a well, a body having its lower end provided with a bore, a movable sleeve telescop- 95 ing said bore, slip means mounted in said body normally covered by said movable sleeve, and means for preventing the upward displace- 100 ment of the sleeve by foreign matter such as mud or slime which may enter said bore, said latter means comprising a wooden pin mounted in the body and extending trans- versely of the bore, said pin being disposed in the path of the upper end of the sleeve and being arranged to be sheared by the sleeve when the sleeve is engaged by the tool part, whereby the sleeve is allowed to enter the up- 105 per end of said bore.
9. In combination, in a device for fishing tool parts from a well, a body member, grip- 110 ping means carried by said body member adapted to engage the tool part to be removed from the well, and means for normally covering said gripping means adapted to be slid upwardly in said body member when it strikes a tool part so as to uncover said gripping means, whereby said gripping means will be allowed to grip the tool part.
10. In combination, in a device for fishing tool parts from a well, a body member, grip- 120 ping means carried by said body member adapted to engage the tool part to be removed from the well, means for normally covering said gripping means adapted to be moved when it strikes a tool part so as to uncover said gripping means, whereby said gripping means will be allowed to grip the tool part, and means for preventing displacement of 125 said covering means by foreign matter such 130

as mud, said latter means being shearable by said covering means upon said covering means coming into contact with the tool part.

11. In combination in a device for fishing
5 tool parts and the like from a well, a hollow body member, wedge means mounted in the inner wall of said body member arranged to grip the tool part entering the same, and means for normally holding said wedge
10 means in an inactive position inside said body member and displaceable by the tool part to allow said wedge means to engage and grip the tool part.

12. In combination in a device for fishing

15 tool parts and the like from a well, a body member provided with a tubular portion to receive the tool part, a contractible ring-like slip disposed within said portion, and means for holding said slip in an expanded position during the lowering of the device in the well and displaceable when it strikes the tool part entering said portion to allow said slip to contract and engage said tool part.

20 25 In testimony whereof I have hereunto subscribed my name at Tulsa, Oklahoma, county of Tulsa.

FRANK J. HINDERLITER.
